UNITED STATES PATENT OFFICE.

MORRIS H. ROSENBERG, OF SAN FRANCISCO, CALIFORNIA.

DESIGN FOR A LAMP BRACKET.

Application filed October 20, 1924. Serial No. 11,131. Term of patent 3½ years.

To all whom it may concern:

Be it known that I, MORRIS H. ROSENBERG, a citizen of the United States, residing in the city and county of San Francisco, and State of California, have invented a new, original, and ornamental Design for a Lamp Bracket, of which the following is a specification, reference being had to the accompanying drawing, forming part thereof. The figure is an elevation showing my improved design.

I claim:

The ornamental design for a lamp bracket as shown.

MORRIS H. ROSENBERG.
